UNITED STATES PATENT OFFICE.

WILLIAM A. WALL, OF CARROLLTON, AND ANNA N. MITCHELL, OF ROCKBRIDGE,
ILLINOIS.

CURTAIN AND QUILTING FRAME.

Application filed May 27, 1922. Serial No. 564,277.

To all whom it may concern:

Be it known that we, WILLIAM A. WALL and ANNA N. MITCHELL, citizens of the United States, residing at Carrollton and Rockbridge, respectively, in the county of Greene and State of Illinois, have invented certain new and useful Improvements in Curtain and Quilting Frames, of which the following is a specification, reference being had to the accompanying drawings.

This invention relates to curtain and quilting frames and has for its object to provide a frame of this character capable of being adjusted to the size desired both longitudinally and laterally.

It is another object of the invention to provide a device of this character having novel means for holding the frame in a horizontal position when in spaced relation to the ground.

It is another object of the invention to provide a device of this character that can be folded in a compact form and wherein the end or holding members of the frame serve as means for connecting the side members of the frame.

It is also an object of the invention to provide a frame of this character including adjustable side beams, said beams being adjustable to increase or decrease the length of the frame without interfering with the connection of the end or holding members to the frame.

It is a further object of the invention to provide a frame of this character wherein one end portion of each of the side beams may be folded or collapsed with respect to the opposite end portion and the end members disengaged to render the device compact for storing purposes.

With these and other objects in view, the invention consists in the improved construction and arrangement of parts to be herein-after more particularly described, fully claimed and illustrated in the accompanying drawings, in which:

Figure 1 is a perspective view of a curtain and quilting frame constructed in accordance with an embodiment of the invention;

Figure 2 is a longitudinal sectional view;

Figure 3 is a perspective view of one of the end or holding members;

Figure 4 is a top plan view of the structure shown in Figure 1;

Figure 5 is a side elevation of the frame in its closed position; and

Figure 6 is an end elevation of the structure shown in Figure 5.

Referring to the drawings, 5 designates a frame including side members 6 and end members 7. Each of the side members or beams 6 consist of a section 8 having a longitudinally extending slot 9 which terminates adjacent each end of the section 8, each end 10 being provided with blocks 11 which cooperate to provide recesses 12 on each side of the section, the purpose of which will be hereinafter described.

The remaining section 13 of the side member comprises a substantially rectangular sleeve or tubular member, the end supporting member 14 of said sleeve or tubular member being solid so as to close the end of the sleeve, the end supporting member 14 similar to the end portion of the section 8 being provided with blocks 15 which cooperate to provide recesses 16 on each side of the end supporting member 14. The section 8 is adapted to telescope the section 13 so as to increase or decrease the length of said side member or beam. A bolt 17 extends through registering openings provided in the end portion 18 of the sleeve and through the slot 9 of the section 8. A wing nut 19 is engaged with the opposite end of the bolt so that upon rotation of the nut toward the sleeve, the walls of the sleeve will be brought into binding engagement with the sides of the section 8 so as to firmly hold the sections in their adjusted positions. It will be noted that only one adjusting bolt is necessary for each beam.

The end supporting member 14 of the section 13 has a mortise or recess 20 in its upper surface, said recess being disposed adjacent the extremity of the section 8. The side members or beams 6 are adapted to be disposed in spaced relation to each other and are connected by means of holding members 7, each holding member consisting of a strip of material having prongs or pins 21 projecting from one face thereof and longitudinally of the strip, said pins being adapted to receive the mate-

rial to be stretched or supported. A second strip 22 is hinged to one longitudinal edge of each of the holding members, said strip 22 having a longitudinally extending recess 5 or groove 23 in one longitudinal face thereof, said groove or recess being adapted to extend over the pins to assist in holding the material in engagement with the pins. The strip 22 thereby serves the purpose of a cap 10 to not only prevent disengagement of the material from the pins, but to prevent contact of the hands of the user with the pins. The ends of each of the strips 7 are adapted to extend into the recesses 20 of the beams, 15 the strips being snugly fitted within the recesses so as to frictionally engage the walls of the recesses 20 and prevent accidental movement of the beams with respect to each other and the holding members.

20 In order that the holding frame may be supported in a position to facilitate the use of the device, there is provided a plurality of supporting members, each member consisting of a pair of legs 25 which are 25 spaced from each other by means of braces 26 and 27, the brace 26 being disposed at the intermediate portion of the legs, while the brace 27 is disposed adjacent the upper portion of the legs to hold the upper 30 ends of said legs in spaced relation to each other. Additional securing means in the form of bars 28 are provided to reinforce the structure of the supporting members. The upper ends of the legs of each of the 35 supporting members is adapted to extend into the recesses 12 and 16 of the side members, the end portions of said side members resting upon the upper brace or reinforcing member of the supporting member. A bolt 40 29 is passed through the upper ends of each of the supporting members and the side members so as to clamp the supporting members and prevent accidental disengagement of the same from the frame.

45 In use, the sections 8 are moved outwardly of the sections 13 and clamped in the desired adjusted position by means of the bolts 19. The holding members 7 are then disposed in the recesses 20, and the supporting means 25 50 applied as previously described. After the device has been set up, if the adjustment of the side members is not proper, the entire frame may be adjusted without disturbing the holding or connecting members 7 by 55 loosening the bolts 19 at the intermediate portion of the frame and adjusting the sections 8 and 13 with respect to each other, without disconnecting the holding or end members from the side members. If the 60 width of the frame is too great for the material, the connecting members may be moved laterally of the ends of the side beams so as to position the side members nearer or farther away from each other according to the 65 size of the material to be engaged with the

holding members. When the device is not in use, the supporting members or legs may be readily disengaged from the side members and the side members telescoped or collapsed and the holding members disposed in parallel relation to the side members whereby the device is rendered compact for storage in a small space.

From the foregoing it will be readily seen that this invention provides a novel device 75 capable of efficiently supporting material for quilting or for stretching lace curtains, without danger of the curtains being made or stretched crooked because of improper adjustment of the frame, as the recesses 20 at 80 the ends of the supporting beams insure the proper right angular position of the holding members with respect to the side beams, the adjustment of the frame being made at the center of the side beams. Furthermore, 85 the holding members are provided with protectors or caps which permit the frame to be used for other purposes, such as horses for supporting an ironing board, or to receive planks to form a table so that its utility is 90 not limited to a curtain or quilting frame and as its parts are simple and substantial it will last indefinitely.

What is claimed is:—

1. A quilting frame comprising side members, each side member consisting of a sleeve substantially rectangular in cross section and open at its ends, one end of the sleeve being closed by a block, the side faces of said block adjacent the ends of the sleeves having cleats for the reception of supporting legs, the upper face of the block adjacent the end thereof having a recess, a supporting rod 95 slidable in the sleeve, said rod having a slot 100 extending transversely of the rod and longitudinally thereof, the opposite end portion of the sleeve having spaced registering openings the supporting rod of each side member being connected to the adjacent supporting rod by an end member, the sleeve members of each side member being connected to each other through the medium of a second end member, a bolt disposed in said openings and in the slot of the supporting rod, the 105 head of said bolt being adapted to engage one side of the sleeve, and a wing nut carried by the opposite end of the bolt and adapted to engage the outer end of the sleeve, the side members of said sleeves being resilient 110 whereby said sleeves may be urged into binding engagement with the rod to hold said rod in various adjusted positions.

2. In a quilting frame, a pair of sectional side beams, each beam consisting of a tubular member substantially rectangular in cross section and having a solid block projecting from one end thereof to reinforce said sleeve and provide a substantial support, a rod 115 slidable in the opposite end of the sleeve, said rod being substantially rectangular in cross 120 section and having a slot extending transversely of the rod and longitudinally thereof, the 125 opposite end portion of the sleeve having spaced registering openings the supporting rod of each side member being connected to the adjacent supporting rod by an end member, the sleeve members of each side member being connected to each other through the medium of a second end member, a bolt disposed in said openings and in the slot of the supporting rod, the head of said bolt being adapted to engage one side of the sleeve, and a wing nut carried by the opposite end of the bolt and adapted to engage the outer end of the sleeve, the side members of said sleeves being resilient 130 whereby said sleeves may be urged into binding engagement with the rod to hold said rod in various adjusted positions.

section and having a longitudinally extending slot, a bolt extending through the side walls of the tubular member at the opposite end thereof and through the slot of the rod, and means carried by the bolt for urging the side walls of the tubular member into binding engagement with the adjacent side portions of the rod, the outer end wall of the

slot of the rod being arranged to engage the bolt to prevent contact of the inner end of the rod with the inner end of the block.

In testimony whereof we hereunto affix our signatures.

WILLIAM A. WALL.

ANNA N. MITCHELL.
